TOILET

Donald B. Hunter, Edgerton, Wis.

Application August 16, 1943, Serial No. 498,758

3 Claims. (Cl. 4—111)

The invention relates to toilets.

The object of the invention is to provide a dry toilet which is simpler than and has advantages over the chemical type toilet. The usual chemical toilet has a metal body portion which rusts out in a few years, and it has to be cleaned every week or more to avoid very objectionable odors due to the action of the chemicals on the sewage. The toilet embodying the invention is particularly adapted for use in conjunction with a septic tank or other suitable sewage disposal apparatus and is rustproof, easily cleaned, and practically permanent and odorless. According to the present invention, the base of what may be termed the bowl is formed of concrete or other suitable non-metallic material, and the sides are formed of sections of glazed tile pipe sections with the seat mounted on the upper section, the base having a flushing opening controlled by a manually operable valve.

The invention further consists in the several features hereinafter set forth and more particularly defined by claims at the conclusion hereof.

In the drawing:

Fig. 1 is a vertical sectional view through a toilet embodying the invention, parts being shown in full;

Fig. 2 is a detailed sectional view taken on the line 2—2 of Fig. 1;

Fig. 3 is a detailed sectional view taken on the line 3—3 of Fig. 1;

Fig. 4 is a detailed sectional view taken on the line 4—4 of Fig. 1.

Referring to the drawing, the numeral 5 designates a base member formed by a slab of concrete or other suitable non-metallic material which may be of rectangular formation and positioned at the bottom of a hole or cavity 6 which extends down several feet below the level of the building floor or ground 7. This base member has a flushing outlet conduit 8 formed therein leading from one side thereof and opening into its top adjacent this side, and the top of the base has its surface 9 inclined toward the inlet of said conduit 8, as shown in Figs. 2 and 3.

A section 10 of glazed tile type of large diameter cylindrical water pipe is placed upon the base, and its lower bell-mouthed end 11 is preferably worked down into the top of said base before the concrete has completely set, and said end is also rendered water-tight by neat cement 12 applied to the joint between said pipe and base. The inlet to the conduit 8 is disposed near one side of said pipe section 10.

A second section 13 of glazed tile type of large

diameter cylindrical water pipe has its bell-mouthed end 13' fitting over the upper end of the pipe section 10 and suitably cemented thereto and to the plane upper end of said pipe section 13 is secured a contractable split metal band 14 whose upper edge projects above the upper edge of said pipe section. The pipe sections 10 and 13 form a hollow shaft projecting above the ground or floor 7.

10 The parts of the band 14 are clamped together by a clamping bolt 15 and a shelf or bracket 16 is welded or otherwise suitably secured to one side of said band and is adapted to take the metal seat fitting members 17.

15 The seat fitting members 17 are in known manner operatively connected to a seat 18 and to a cover 19 pivotally mounted relative to said seat. The seat 18 rests upon the upper edge of the band 14.

20 A vent pipe 20 has its lower end projecting into an opening 21 in the upper portion of the pipe section 13 adjacent the seat and is suitably cemented thereto.

25 The toilet is of the dry type, but its contents are adapted to be flushed out through the outlet conduit 8 when desired. This outlet conduit 8 is preferably connected with a septic tank or other suitable sewage disposal apparatus.

30 To seal off the conduit 8 a manually operable valve 22 is provided which is formed by the usual rubber head suction type plunger having a long wooden handle 23 which projects upwardly through the pipe sections adjacent one side thereof, out of the way, to a position where it may be manipulated from above the toilet when it is desired to introduce water therein to flush the contents out through the conduit 8. After the flushing operation, the valve 22 is re-seated, and the toilet left in a dry state until the next time it needs to be cleaned. It has been found that a toilet constructed as above described is practically odorless, always looks neat and clean, and has a relatively long life.

35 I desire it to be understood that this invention is not to be limited to any particular form or arrangement of parts except in so far as such limitations are included in the claims.

40 What I claim as my invention is:

45 1. In a toilet of the character described, the combination of a base of non-metallic material having an eccentrically disposed outlet conduit leading therefrom, glazed tile piping mounted on and having fluid-tight connection with said base and extending to a point above the ground or floor level, a seat mounted on the upper end of said piping, and manually operable valve

means within said piping normally sealing off said outlet conduit and operable from the upper end of said piping.

2. In a toilet of the character described, the combination of a base of non-metallic material having an outlet conduit leading therefrom, glazed tile piping having fluid-tight connection with said base and extending to a point above the ground or floor level, a split metal ring clamped to the upper end of said piping, and 10

3. In a toilet of the character described, the

combination of a base of non-metallic material having an eccentrically disposed outlet conduit leading downwardly from the top thereof, a non-metallic hollow shaft extending from said base to a point above the ground or floor level, a seat mounted on the upper end of the shaft, and a bodily displaceable valve sealing off said outlet conduit and having a long handle projecting upwardly in said shaft at one side to a position where it may be manipulated from the upper end of said shaft.

DONALD B. HUNTER.
